HAROLD P. HAYDEN, OF PERTH AMBOY, AND WAYNE W. WEAVER, OF RAHWAY, NEW JERSEY, ASSIGNEES TO THE BARBER ASPHALT COMPANY, OF PHILADELPHIA, PENNSYLVANIA A CORPORATION OF WEST VIRGINIA.

FLEXIBLE SHINGLE.

Application filed December 30, 1924. Serial No. 758,812.

This invention relates to flexible shingles and it has more particular reference to those types adapted to be laid diagonally, said types usually having a bent underflap and a connected securing strip arranged to extend under and engage portions of adjoining units in an underlying row thereof.

Shingles of the class referred to while successful in so far as holding down the free ends when laid so as to counteract buckling are difficult to pack for shipment without considerable waste of space. Furthermore the securing strip or attaching staple frequently gets damaged with the result that many of the shingles when unpacked require straightening and other attentions before being in correct condition for laying.

The primary object of our invention is to provide flexible shingles of the foregoing typified character embodying novel features whereby they may be compactly stacked for storage or shipment with the underflap and attached securing means wholly protected from injury and displacement.

Other objects and advantages will be apparent on examination of the drawings, constituting a part hereof, as well as clearly appreciated from the following description of a selected example chosen, from among other possible embodiments, as conveniently suited to advantageously illustrate the novel characteristics of our invention.

In the drawings; Fig. I, is a perspective view of a flexible shingle embodying the present invention.

Fig. II, is an illustration showing the manner in which the flexible shingles of our invention may be economically cut from a continuous strip of double-width material.

Fig. III, is a view in plan showing the manner in which our novel form of shingles may be stacked with the underflap of one shingle interfitting the cut-out of another.

Fig. IV, is a side elevation exemplifying the advantages inhering to the manner of packing our novel shingles; and,

Fig. V, is a fragmentary plan view, more or less diagrammatically represented, showing the manner in which the improved shingles are laid.

Referring more in detail to the drawings

it will be seen that the individual shingles—comprehensively designated by the numeral 6—are of the "diamond" type, but it is to be explicitly understood that our improvements are not restricted thereto, they being equally well adapted to all shingles generally known as "point down" forms. Each shingle 6, may be conveniently fabricated from any of the well known single or double-width materials used in the art, but by way of example, let it be assumed they are made of asphalt impregnated felt having a mineralized coating on one surface. As shown, each shingle 6 is generally rectangular in outline with one corner retroverted along a crease 7 to provide an underflap or tip 8, through which the securing means or staple 9 is forced. The securing means or staple 9 it will be noted is preferably made of flat strip material medially bent and driven through the tip 8—before retroversion—at 10, then flattened out to afford aligned ends 11, 11, disposed parallel with the aforesaid crease 7—and lying wholly within the confines of the shingle side edges 12, 12.

The diagonally opposed corner of each shingle 6, tipped as set forth in the preceding paragraph, is cut away at 13 to provide an angular or V-shaped recess 14, with the apex 15 thereof directly in line with the vertical diagonal of said shingle when laid. In other words the angular recess 14 permits less of the shingle being cut-away while affording a definite point 15 for alignment when positioning on the vertical chalk lines 16—Fig. V—while it further serves as a means to accommodate the tip 8 of the adjacent shingle when stacked—or in package form—as will be readily understood on examination of Figs. III and IV. This feature of our invention is deemed of considerable importance for economic as well as utilitarian reasons, economic in that less material is cut away to waste and utilitarian by reason of its effectiveness to prevent relative lateral displacement of superposed shingles when stacked or packed for shipment. Furthermore it will be clearly discernible from Fig. III, that when one shingle 6 is laid end-to-end upon another the point of the underfold or tip 8 repose snug-

ly in the apex 15 of the recess 14, while the free ends 11 of the securing means 9 are wholly accommodated in the triangular spaces 17 afforded at each side by the tip 8 and the cut-off edges 18.

Shingles 6 configured and fabricated as above set forth may be cut from single width material in rectangular units by an appropriate cutter which removes the corner 13 and forms the V-shaped recess 14 at one operation, then turned about to have the securing means 9 stapled into the diagonally opposed corner, previous to retroverting the tip 8 in a bending machine. Or, shingle 6 may be cut by a suitable shaped cutter from double width material 19 as shown by Fig. II the only waste consisting of the eight-pointed star portions 20 intermediate four adjoining shingles.

In shingling a roof or other surface Fig. V—with flexible shingles 6 shaped and made, in accordance with the present invention, each successive course is laid by placing a unit 6 of the next upper course over two units of the next lower course in a position for the free ends 11 of the securing means 9 to pass under the two adjacent lower shingles S S. The shingle 6 is next pulled upwards with the aforesaid free ends 11 engaged below the adjacent convergent edges of the shingles S S—previously attached in place by nails 22—thereby effecting a secure, interlock with the lower course. The shingle 6, it is to be particularly observed, is correctly aligned by manipulating the apex 15 of the V-shaped recess 14 into registration with the chalk line 16 hereinbefore referred to, and nailed down at its side corners by nails 22, whereupon the same operations just described are repeated.

From the foregoing description it is thought that our invention will be fully understood, but among the numerous advantages inhering thereto attention is directed to the fact that perfectly square and compact packages may be cheaply produced. When the shingles 6 are stacked, or packed for shipment, the securing means 9 do not project beyond the edges of said shingles thus eliminating all danger of bending while the interfitting of the tip point into the recess 14 ensures no projecting corners and prevents lateral displacement whereby a tighter and more solid bundle is readily made. Incidentally weight is reduced, while the recess 14 enables correct side alignment when shingling a surface to be covered.

While we have described one practical embodiment of this invention we do not confine ourselves to the precise details shown, but reserve the right to make such changes

and variations as are fairly encompassed by the scope of the subjoined claims.

Having thus described our invention, what we claim is:—

1. A flexible shingle having a retroverted tip with an interfitted laterally directed securing member, and an opposed cut-out affording a recess functional as an aligning point and adapted to receive the retroverted tip apex of an overlying shingle when stacked. 70

2. A shingle having a retroverted tip with an interfitted laterally directed securing member, and a diagonally opposed cut-out 75 affording an angular recess adapted to accommodate the tip apex of a superposed shingle when stacked.

3. A point-down shingle having an underfolded tip with an interfitted laterally directed securing member, and a diagonally opposed cut-out affording a centrally located V-shaped recess adapted to accommodate the tip apex of a superposed shingle when stacked. 80

4. A point-down shingle having an underfolded tip with an interfitted laterally directed securing member the free ends whereof are wholly within the confines of the shingle side edges, and a diagonally opposed cut-out 90 affording a centrally located V-shaped recess adapted to accommodate the tip apex of a superposed shingle when stacked.

5. A point-down shingle having an underfolded tip with an interfitted laterally directed securing member, and a diagonally opposed cut-out affording a V-shaped recess 95 functional to correctly align said shingle when laid as well as to accommodate the tip apex of a superposed shingle when stacked.

6. Shingles having retroverted tips with interfitted laterally directed securing members, and opposed cut-outs affording recesses adapted to accommodate the tip apices of superposed shingles, whereby said shingles may be closely compacted for storage and shipment as well as effectively prevented from relative lateral displacement. 105

7. A point-down shingle having an underfolded tip with an interfitted laterally directed securing member, and a diagonally opposed cut-away affording a centrally located V-shaped recess, said cut-away and recess being adapted to accommodate the tip apex and interfitted securing member of a superposed shingle when stacked. 110 115

In testimony whereof, we have hereunto signed our names at Maurer, N. J., this 22nd day of December, 1924.

HAROLD P. HAYDEN
WAYNE W. WEAVER
